UNITED STATES PATENT OFFICE.

JOHN ELSTON RHODES, OF TEANECK, NEW JERSEY.

CLASP.

Application filed July 19, 1922. Serial No. 575,927.

To all whom it may concern:

Be it known that I, JOHN ELSTON RHODES, a citizen of the United States, and a resident of Teaneck, county of Bergen, and 5 State of New Jersey, have invented a certain new and useful Improvement in Clasps, of which the following is a description.

This invention relates to clasps, and more particularly to clasps of that character generally used in connection with stocking or 10 hose supporters.

It is the primary object and purpose of my present improvements to provide a clasp of very simple construction consisting of 15 two complementary parts having co-acting means operating to securely hold or grip the stocking either when the same is subjected to tensional pull or when it is comparatively loosely held, and without danger of breaking the threads of the fabric or otherwise injuring the stocking.

My invention further contemplates the provision of a clasp for stockings or other fabric articles which is of such construction 20 that although the two parts of the clasp may be manually manipulated and easily connected or disconnected, said parts when in assembled relation upon the stocking will not be liable to accidental disconnection so 25 that the stocking may be released.

It is a further general object of the invention to provide a device of the above character which is of exceedingly durable construction and which, when applied and 30 in use, will be inconspicuous. To this end, I preferably make the parts of the clasp from imitation ivory, celluloid or other suitable composition material which may be 35 readily colored so that the parts of the clasp will harmonize with the color of the stocking or other garment.

With the above and other objects in view, the invention consists in the improved clasp and in the form, construction and relative 40 arrangement of its several parts as will be hereinafter more fully described, illustrated in the accompanying drawing and subsequently incorporated in the subjoined claims.

In the drawing wherein I have illustrated 45 several satisfactory and desirable embodiments of the invention and in which similar reference characters designate corresponding parts throughout the several views:

Figure 1 is an elevation showing one form of the invention that is used in connection with a hose or stocking supporter; 55

Figure 2 is a section taken on the line 2—2 of Figure 1;

Figure 3 is a similar view showing the relative position of the parts in the act of 60 clasping the stocking fabric;

Figure 4 is a detail elevation of the clasp showing the parts separated; and

Figures 5, 6 and 7 are views corresponding to Figs. 1, 2 and 3 respectively, showing another way in which the parts of the clasp may be connected to the elastic webbing of the hose supporter. 65

Referring in detail to the drawing and more particularly to Figures 1, 2 and 3 70 thereof, I have shown the lower end portion of the elastic webbing 5 of a stocking supporter such as is usually employed in connection with ladies' corsets. This webbing is provided with an elongated metal loop 6 75 which is formed at its lower side with an eye 7 through which an inelastic strap 8 is engaged.

The stocking clasp as herein shown, includes two complementary parts 9 and 10 80 respectively. The part 9 tapers longitudinally or is of gradually decreasing width from one end to the other and at its wider end is provided with a rectangular opening 11. The narrower end of the part 9 85 is formed with an eye 12 in which one end of the strap or tape 8 is permanently secured. The other part 10 of the clasp likewise tapers or gradually decreases in width from one end to the other, the narrower end 90 of said part being of appreciably less width than the length of the opening 11 in the part 9. This narrower end of the part 10 terminates in a relatively thick neck portion 13 extending at right angles to the plane 95 of said part and having a thickness appreciably less than the width of the opening 11 in the part 9 as will be seen from reference to Figure 2 of the drawing. The end of this neck 13 is formed with a relatively broad flat rectangular head providing flanges 14 at the opposite sides of said neck portion, the width of said head being appreciably greater than the width of the opening 11. At its wider end the part 10 100

is likewise provided with an eye 15 to which 105

the other end of the strap or tape 8 is permanently attached.

- In the application of the clasp to the stocking, the part 9 is disposed upon the 5 outer side of the stocking fabric at its upper edge and part 10 on the inner side thereof. While the part 9 is held in a substantially vertical position, the part 10 is moved to an angular position with relation thereto, 10 as seen in Figure 3 of the drawings until the flanged neck 13 thereon may be projected outwardly through the opening 11 in the part 9. The stocking fabric or material may thus likewise be forced outwardly through 15 said opening so that when the parts of the clasp are disposed in parallel relation to each other, as seen in Fig. 2, the stocking material extends around the flanges 14 and is gripped or held between the same and 20 the part 9 of the clasp at the opposite edges of the opening 11 therein. The flanged head of the neck 13 provides a relatively wide area with which the stocking material has frictional contact. It is further to be noted 25 that the material has frictional gripping engagement with the neck 13 and the edge of the opening 11 substantially for the entire length of said opening so that a great number of threads of the fabric are friction- 30 ally engaged or gripped by the parts of the clasp, thereby distributing the strain, and to a great extent, obviating liability of breakage of the threads and tearing of the stocking fabric as would be likely to occur 35 if the entire gripping strain was applied to only a small number of the fabric threads. Due to this extensive area of frictional contact of the stocking material with the parts of the clasp, the stocking is held against 40 movement or slipping between the interlocked parts of the clasp even when there is no strain or pull upon the stocking. Thus, when the wearer assumes various postures, the parts of the clasp will always remain 45 in their initially applied positions relative to the upper edge of the stocking or, in other words, there will be no relative movement between the stocking and the clasp.
- It will further be observed that since the 50 part 10 tapers in an opposite direction with respect to the part 9 of the clasp, the projection of the neck portion 13 through the opening 11 will be limited by the approach of the side edges of the part 10 to the end 55 edges of the opening 11 in the part 9. Therefore, only the requisite amount of the stocking material to extend over the flanges 14 will be projected through said opening and it will not be necessary to subsequently adjust 60 just the stocking after the parts of the clasp have been connected. Since it is possible to connect the parts of the clasp only when they are disposed in predetermined angular relation to each other, as seen in Figure 3, 65 it will be apparent that the possibility of

the clasp parts accidentally moving from their normal positions, as seen in Figure 2, to such relative angular positions where they might become disconnected, is practically eliminated. However, the parts of the clasp 70 may be manually disconnected by a reversal of the operation above described.

In Figures 5, 6 and 7 of the drawings I have shown an alternative embodiment of the invention wherein one end of the in- 75 elastic tape or strap 8' is permanently attached to the loop 6 carried by the elastic webbing, while the other end of this tape is permanently attached to the clasp member 9. In this instance, the tape or strap 80 8' is loosely engaged through the eye 15' in the end of the other clasp member so that said member may be readily shifted upon the tape to the proper angular position with relation to the complementary clasp 85 member for the purpose of connecting or disconnecting said members, as shown in Figure 7 of the drawing. The application and manner of operation of the device is otherwise identical with that previously referred to.

From the foregoing description considered in connection with the accompanying drawing, it will be seen that I have produced an exceedingly simple, durable and easily oper- 95 able clasp for use in connection with stocking supporters and for various other analogous purposes. The parts of the clasp may be made in various sizes and of metal, celluloid, imitation ivory or other suitable 100 materials. Also, it is not essential that the complementary parts or members of the clasp shall have the particular shape or form herein shown, though I have found in practice that such form of said members 105 gives the best results in actual use. When the parts are connected, they lie perfectly flat and will, therefore, occasion no inconvenience or discomfort to the wearer. They also may be readily colored so as to harmonize with material of the stocking or 110 garment.

While I have herein shown and described several satisfactory and preferred embodiments of the invention, it is nevertheless to 115 be understood that the device may also be incorporated in numerous other alternative structures, and I accordingly reserve the privilege of resorting to all such legitimate changes as may be fairly embodied within 120 the spirit and scope of the invention as claimed.

I claim:

1. A clasp of the character described, comprising two complementary parts, one of 125 said parts having a rectangular opening and the other of said parts terminating at one of its ends in an angularly extending neck having flanges at its opposite sides and extending the full length of said neck, the flanged 130

- portion of said neck being of greater width than the width of said opening and adapted to be projected through said opening of the first named part only when said parts are disposed in certain predetermined relative angular positions and said flanges overlying the opposite edges of said opening when the parts are subsequently arranged in substantially parallel relation to each other.
- 10 2. A clasp of the character described, comprising two complementary parts, one of said parts having a rectangular opening, and the other of said parts terminating at one of its ends in an angularly extending neck corresponding in form to said opening, but of slightly less dimensions to substantially occupy the entire area of said opening and said neck having a portion of greater width than the width of said opening to prevent movement of said neck through the opening when said clasp parts are disposed in other than certain predetermined relative angular positions, said neck extension and the first named part frictionally co-acting with the material engaged by the clasp along substantially the entire length of said opening when the clasp parts are arranged in parallel connected relation.
- 30 3. A clasp of the character described, comprising two complementary parts, one of said parts having an elongated opening and the other of said parts terminating at one of its ends in an angularly extending neck corresponding in form to said opening but of slightly less dimensions and said neck having oppositely projecting flanges, the flanged portion of the neck being of greater width than the width of said opening to prevent movement of said neck through the opening when said clasp parts are disposed in other than certain predetermined relative angular positions, said neck and its flanges and said first named part frictionally coacting with the material engaged by the clasp parts and having binding engagement therewith along substantially the entire length of said opening at one side thereof when the clasp parts are arranged in parallel connected relation.
- 50 4. A clasp of the character described, comprising two complementary parts, one of said parts being provided with an opening and the other part terminating at one of its ends in an angularly projecting head having a neck portion connecting the head intermediate the longitudinal edges thereof to the body of said part and adapted for interlocking engagement through said opening, and said parts being constructed to provide means coacting to positively limit the extent to which said second named part may be projected through said opening in the operation of effecting an interlocked relation of the parts.
- 55 5. A clasp of the character described, comprising complementary parts, each gradually decreasing in width from one end to the other, one of said parts being provided with a rectangular opening in its wider end and the other of said parts terminating at its narrower end in an angularly projecting head including a neck having a flange at each side thereof extending the entire length of said neck and providing a portion of greater width than said opening and adapted to be projected through said opening when the parts are arranged in predetermined relative angular positions, the divergent side edges of said second named part acting to limit the distance to which said terminal head may be projected beyond said openings by the coacting of said divergent edges with the end edges of the opening, the flanges of said terminal head overlying the opposite side edges of said opening when the parts are disposed in substantially parallel relation and said head having frictional gripping contact with the material engaged between said parts along one edge of said opening substantially over the entire length thereof.
- 60 70 75 80 85 90 95
- In testimony that I claim the foregoing as my invention, I have signed my name hereunder.

JOHN ELSTON RHODES.
